HYDRAULIC SPADER AND AGITATOR FOR
CONCRETE BLOCK MACHINES

Thomas B. Sansbury, Orlando, Fla.

Application July 12, 1948, Serial No. 38,296

5 Claims. (Cl. 25—41)

1

This invention relates to a concrete block machine and has special reference to a concrete block machine which is an improvement on my prior application for patent, Serial No. 781,923.

In my prior application for patent I employed certain stirrers which were intended to have a rotary movement over the surface of the material deposited in the mold.

One important object of the present invention is to improve the action of these stirrers by giving them a swinging or rotary oscillatory movement.

Another important object of the present invention is to provide hydraulic means which may effect simultaneous rotary oscillations or swinging movements of the stirrers and reciprocation of the spaders.

A further important object of the invention is to provide means which are purely hydraulic for controlling the operation of the device.

With the above and other objects in view that will become apparent as the nature of the invention is better understood, the same consists in the novel form, combination, and arrangement of parts hereinafter more fully described, shown in the accompanying drawings, and claimed.

In the accompanying drawings,

Figure 1 is a front elevation of the improved block molding machine,

Figure 2 is a side elevation thereof partly broken away.

Figure 3 is a view on the line 3—3 of Figure 1, showing the means for oscillating the spader,

Figure 4 is a horizontal sectional view taken on line 4—4 of Figure 1,

Figure 5 is a fragmentary elevational view of one means of controlling the hydraulic flow,

Figure 6 is a partial elevation showing the arrangement of the transverse frame, and the spaders, and modified stirrers, and

Figure 7 is a detailed section on the line 7—7 of Figure 6.

In the form of the invention as here shown there is provided a base 10 on opposite sides of which are supported vertical frame members 11. Attached to these frame members 11 by clamping collars 12 are diagonal brace members 13 the lower ends of which are welded or otherwise secured to the base 10. The upper ends of the members 11 are connected by a yoke 14. The lower parts of the members 11 are connected to the mold box and machine frame as shown at 15 in general, the connections including upper collars 16 braced to the base by diagonal braces 17 which also act as limit stops for a structure presently to be described, and lower collars 18 55

2

carrying brackets 19 between which is located the mold box 20.

The members 11 are preferably of tubular cross section and slidable vertically on the members 5 11 is a spader and agitator carrier frame shown in general at 21 which includes sleeves 21a slidable on the members 11 carrying brackets 22 which, in turn, carry side frame members 23 connected at their ends by cross frame members 24. Vertical members 25 connect the upper and lower parts of this frame.

Carried by the yoke 14 is a vertical cylinder 26 wherein reciprocates a piston 27 actuating a rod 28 in vertical reciprocating movement. On the lower end of the rod 28 is carried a spider 29. Connecting the members 24 is a pair of tie bars 30 and these tie bars 30 carry sleeves 31 wherethrough slide rods 32. The lower ends of the rods 32 are secured in sockets 33 on the upper ends of two arched yokes 34, by means of set screws 35. The lower ends of the yokes 34 carry two rectangular spader frames 36 having inner bars 37 and outer bars 38 forming, in effect, a pair of rectangular spaders mounted to reciprocate on fixed vertical paths.

Attached to the lower end of the piston rod 28 is a camming member 39 having a centrally disposed vertical slot 40, the lower portion of which is of zig-zag form as seen at 41. Slidable vertically with respect to the member 39 is a yoke-bar 43 through the center of which runs a bolt 44 carrying a roller 45 which extends through the slots 41 and 42. The lower members 24 are connected at each side of the camming device 39 by tie-bars 45' carrying pivot brackets 46 whereto are pivoted bell crank levers having depending legs 47 and upstanding L-shaped legs 48 the upper ends of which are pivotally connected to the ends of the yoke-bar 43. By this means vertical reciprocation of the piston rod 28 causes rocking of the bell crank levers. Fixed in the arms 47 of the bell crank levers are depending rods 49 carrying at their lower ends agitating elements 50. Rocking of the bell cranks thus causes oscillation or swinging movements of these elements 50. The combined action of the elements 50 with the spaders 36 ensures complete spading of the mix in the mold and prevents the formation of voids so that the resultant product is of uniform density throughout.

In Figures 6 and 7 modified agitators are shown. In this case carried by the members 24 are bearings 51 wherein are rotatively mounted shafts 52 suitably held against longitudinal movement in said bearings. Projecting from the lower ends of

the shafts are rods 53 having agitating blades 54 at their lower ends. The spider has arms 55 carrying sleeves 56 slidably mounted on the shafts 52. Each shaft 52 has cut therein a spiral groove 57 and each sleeve 56 carries a key 58 fitting in the groove 57 so that reciprocation of the spider and sleeves 56 causes rotation of the shafts 52 and consequent rotation of the blades 54.

By either of the means above described the molding materials are forced over and under the spading bars 36 thereby causing the molding material to be packed higher than the strike-off line at the top of the mold box so that the molded block, when ejected or removed, has a flat top surface with sharp edges and such block is of uniform density throughout.

It will be appreciated that the molding materials are piled to a height sufficiently above the plane of the molding box to permit this piled material to be affected by the agitators when the hopper is positioned thereabove. The oscillatory motion of the agitators is such that the material is evenly distributed within the molding boxes and is particularly effective in filling up the corners and voids to obtain a completely uniform density throughout.

Carried by the braces 13 is a plate 59 whereon is mounted a hydraulic control valve 60, one end of which has connection through the pipe 61 with the upper end of the cylinder 26 while its other end is connected with the lower end of said cylinder through the pipe 62. Also mounted on the plate 59 is a cylinder 63 having one end connected, through a branch 64, by a pipe 65 with the pipe 61. The cylinder 63 is carried by a frame 66 and in this cylinder is a piston 67 carrying a rod 68 guided at its free end by the frame. On the rod 68 adjacent the cylinder 63 is adjustably screwed a nut 70 between which and one end of the frame 66 a coiled spring 71 is disposed around the rod 68. On the frame 66 is mounted a bracket 72 and a lever 73 is pivoted intermediate its ends to this bracket. One arm of this lever is engaged by the end of the rod 68. Pivoted to the plate 59 at 74 is a T-shaped lever 75 the stem of which is normally horizontal and the head normally vertical. The stem of this lever projects away from the valve 60 and is connected thereto by a tension spring 76 normally aligned over the pivot so that, if the lever be biased to a past-dead-center position, the spring will bias it to its fullest possible extent. A pin 75a mounted as hereinafter described, is provided to bias this lever downwardly. The lower arm of the head of this lever is connected by a link 77 with the upper arm of the lever 73. The lever 75 constitutes the valve control lever. The upper arm of this lever 75 is provided with pin 78 spaced above the pivot 74. The valve 60 is provided with a stem 79 fixed to an L-shaped member 80 having a horizontal arm formed with an arcuate slot 81 through which the pin 78 extends. The member 80 also has an upstanding arm working in a slotted bracket 82.

Mounted as hereinafter described is an operator's lever 83 having an upstanding forked end 84 adapted to straddle the pin 78 as the frame 21 reaches its maximum upper position after the spading and agitating operations have been performed with said frame 21 in its maximum lowered position.

The above-mentioned pin 75a is carried by a collar 85 which is manually adjustable upon the upper end of a vertical bar 86, said bar 86 being secured to the outer end of an arm 87. This arm 87 is secured to the spider 29. The pin 75a is

cooperative with the upper edge of the lever 75 to force this lever down past dead-center and allow the spring 76 to act to trip valve 60, when said spider nears the limit of its downward movement, thereby reversing the travel of the piston 27 and causing ascent of the piston-actuated parts. Tripping of this valve upon ascent of these parts, to again cause descent of the latter, is effected by means now to be described.

The vertical bar 86 carries a second manually adjustable collar 88 upon which a lever 89 is fulcrumed at 90, and the front end of the lever 75 is provided with a pin 91 for coaction with the upper end of said lever 89. When the piston-actuated parts have been lifted until lever 89 engages pin 91 and forces lever 75 upwardly past dead-center, the spring 76 acts to trip the valve 60, thereby again causing descent of the piston 27 and parts actuated thereby. The lever 89 is spring-held in such position that it will strike the pin 91 unless moved from said position. However, a T-shaped hand lever 92 for this latter purpose is provided, said lever 92 being fulcrumed on an arm 93 secured to frame 21 to swing said lever 89 to an idle position in which it will not strike said pin 91 when the desired agitating and spading have been performed, thereby permitting maximum ascent of the piston to a position in which it lifts the entire frame 21 and parts carried thereby, well above the mold, for block ejection and mold refilling by conventional means. When frame 21 nears its maximum upper position, the forked end 84 of lever 83, which lever is mounted on the lower end of bar 86, engages the pin 78 and swings the lever 75 to move valve stem 79 to its neutral position, insuring that the frame 21 and parts carried thereby shall remain in their fully raised positions while ejecting the completed block and recharging the mold. After recharging the mold, the operator uses the lever 83 to move the lever 75 to piston-lowering position.

The depth of the travel of the spader frames 36 in the mold box 28 and automatic pressure in the fluid cylinder 26 are controlled by the hydraulic valve 60. As the pressure builds up from resistance caused by the molding material being compacted in mold box 28 the pressure is automatically built up in the top of cylinder 26 through feed line 64, which causes pressure to be increased in cylinder 63 through connecting feed line 65, causing piston 67 to create an extended pressure against pressure adjusting spring 71 and connecting rod 68. When connecting rod 68 is extended by reason of increased pressure in cylinder 26 said connecting rod 68 exerts force against lever 73 which downwardly trips valve control lever 75 through connecting link 77. With control lever 75 thus having its stem in down position spader frames 36 are forced in an upward direction caused by fluid being directed by control valve 60 through line 62 into the lower end of cylinder 26 causing piston and connecting rod 28 to move upward, thereby lifting spader frames 36. When spader frames 36 travel upward in carrier frame 21 until stop-actuated control lever 75 is upwardly tripped by lever 83, this automatically reverses valve action, thereby forcing fluid into top of cylinder 26 through line 61, thereby causing a reverse action. The downward motion of spader frames 36 will continue until pin 75a strikes and downwardly trips lever 75, which again automatically reverses action of control valve 60 which thereby reverses spader frame action. This vertical reciprocatory action of the spader frames and concurrent operation

of the agitators will continue automatically until operator moves lever 92 carried on frame 21 and holds it in position to cause lever 89 to clear pin 91, which allows the complete spader assembly to move upward with carrier frame 21 which is also lifted until forked end 84 in lever 83 straddles pin 78, automatically bringing valve 60 to neutral or shut off position which stops spader action and holds same in upper position for clearance while extracting molded block or shape from mold box 19. Material hopper (not shown) with new supply of molding material is now moved over mold box; operator actuates lever 83 forcing pin 78 and member 80 back by fork 84 on lever 83, starting action of valve 60 and forcing fluid into top of cylinder 26 through line 61, piston and connecting rod 28 now being moved downward forcing spader frames 36 down and at the same time allowing carrier frame 21 to move downward by gravity until it comes to rest on stops 17. Spader frames 36 continue downward until pin 15a strikes lever 75 forcing the stem of lever 75 down and reversing action of valve 60 thereby starting complete automatic action of spader and agitator again. Each time the spider 29 carrying the spader frames 36 ascends or descends within the limits dictated by the setting of the collars 85 to 88, the agitators are operated.

It will be noticed that while one form of automatic valve control has been disclosed here, other forms such as include rotary valves may also be used.

What is claimed is:

1. In a concrete block machine, a base, upright frame members fixed to and extending upwardly from said base, a yoke connecting the upper ends of said frame members, a hydraulic cylinder carried by said yoke, a transverse frame carried by said frame members, a cross head vertically reciprocable in said transverse frame, a piston rod connecting said cylinder and cross head, a valve controlling the action of said cylinder, a bar carried by the cross head and controlling said valve, vertical shafts mounted in said transverse frame, agitator blades carried by the lower ends of said

5 shafts, camming means associated with the lower end of said piston rod and operated thereby for causing oscillatory motion of said agitator blades, and spader elements carried by said cross head and reciprocating therewith.

2. A concrete block machine as in claim 1, wherein the camming means is carried by the piston rod and transverse frame.

3. A concrete block machine as in claim 1, 10 wherein the spader elements include shafts vertically slidable in the transverse frame and fixed to said cross head.

4. A concrete block machine as in claim 1, 15 wherein said camming means includes levers carried by the transverse frame for the support of said shafts, a member at the lower end of the piston rod having a cam slot therein and a yoke pivotally attached to the upper ends of said levers and having a part extending through the cam slot 20 in said member for operation of said agitator blades.

5. A concrete block machine as in claim 1, 25 wherein said shafts are journaled in the transverse frame and said camming means includes spiral grooves in said shafts and pins carried by the cross head extending into said grooves for causing rotation of said shafts first in one direction and then in the other direction.

THOMAS B. SANSBURY.
